22 Claims. (Cl. 175—363)

This invention relates in general to improvements in control systems and more particularly to means for controlling the power factor of the current in alternating current circuits including electron discharge devices.

In systems employing electron discharge devices such as alternating current rectifying systems, direct current inverting systems, motor control systems, etc., at least a part of the circuits of the system receive alternating current at a power factor which generally depends on the nature of the system and which may reach very low values when the flow of current through the discharge device is regulated by discharge controlling means. It is generally desirable, to raise the power factor of the current to values approaching unity, and it may also be desired to compensate the flow of lagging currents in circuits indirectly connected with the system or to cause flow of leading current through transmission circuits for improving the voltage regulation thereof. Such results are preferably obtained by means of electron discharge means provided with two groups of anodes through which the flow of current is regulated by discharge controlling means in a manner such that the flow of current through the circuits associated with one group of anodes occurs at a lagging power factor and the flow of current occurring through the circuits associated with the other group of anodes occurs at a leading power factor. If the discharge device is of the vacuum type, the flow of current may be controlled by the usual type of control electrode or grid. If the device is however of the vapor type, the flow of current can only be controlled by particular types of control electrodes operable to interrupt the flow of current through the associated main electrodes. The control means should preferably cooperate with any means utilized for regulating the operation of the system and with any means utilized for protecting the system upon occurrence of disturbances therein.

It is therefore among the objects of the present invention to provide an improved control system for an electron discharge device whereby the power factor of the current flowing through the alternating current circuits of the system may be controlled at any desired value.

Another object of the present invention is to provide an improved control system for an electron discharge device whereby the current flow in the alternating current circuit of the system may be maintained at unity power factor.

Another object of the present invention is to provide an improved control system for an electron discharge device whereby currents flowing in the alternating current circuits of the sys-

tem include currents at both leading and lagging power factors.

Another object of the present invention is to provide an improved control system for an electron discharge device whereby the device may operate as an alternating current rectifier or a direct current inverter having an output voltage regulated independently of the power factor of the current in the alternating current circuit thereof.

Objects and advantages other than those above set forth will be apparent from the following description when read in connection with the accompanying drawings, in which:

Figure 1 diagrammatically illustrates one embodiment of the present invention applied to the control of an electron discharge device operable as an alternating current rectifier or a direct current inverter and whereby the alternating current flowing between an alternating current line and the device is maintained at substantially unity power factor; and

Figure 2 diagrammatically illustrates a modified embodiment of the present invention operable for regulating, at will, the power factor of the current flowing between an alternating current line and two electron discharge devices operating in parallel as alternating current rectifiers or direct current inverters.

Referring more particularly to the drawings by characters of reference, reference numeral 6 designates an alternating current line of any desired number of phases and operating at a suitable voltage of any desired frequency, and which is to supply current to or receive current from a direct current line 7, 8. The relative potentials of conductors 7 and 8 will then depend on the direction of the flow of energy between the two lines as is well known in the art. Line 6 is connected with the primary winding 9 of a transformer designated generally by 11 and having a plurality of secondary windings 12, 13, 14 and 16, each comprising a plurality of phase displaced sections connected in star to form a neutral point. The several sections of windings 12 and 13 constitute a six-phase system of which the neutral points may be connected directly or, preferably, through an interphase transformer 17 to cause simultaneous flow of current at every instant through both windings 12 and 13 as is well known in the art. Windings 14 and 16 likewise constitute a six-phase system having two neutral points connected either directly or through an interphase transformer 18. Some of the windings may be provided with taps and may be different from the remainder of such windings but in the present embodiment it will be assumed that the four windings are of similar construction to deliver terminal voltages of equal magnitudes.

Interphase transformers 17 and 18 are provided with mid-taps which are connected with conductor 7 either directly or, preferably, through an interphase transformer 19 to cause simultaneous flow of current at every instant through windings 12 and 13 and through windings 14 and 16. The winding of interphase transformer 19 is constituted of two portions which may have different numbers of turns and of which one portion may be provided with taps, but such portions will be constructed with equal numbers of turns if the electrical characteristics of windings 12 and 13 and of windings 14 and 16 are identical. The phase portions of windings 12 and 13 are severally connected with anodes 21 of an electron discharge device 22 having a cathode 23 connected with conductor 8. In considering the operation of the system herein described it will be assumed that the electron discharge device 22, which will be referred to as rectifier 22 for the sake of brevity, is utilized for supplying line 7, 8 with rectified current obtained from line 6. Such current is supplied to suitable current consuming devices (not shown) which will generally be connected between conductors 7 and 8. If the current consuming device is an electric motor, some of the windings thereof may also be connected between transformer 11 and anodes 21 as is well known in the art.

The flow of current through each anode 21 is controlled by means of a control electrode 24 of a type operable to interrupt the flow of current through the anode at will upon energization of the control electrodes at a suitable potential from a suitable source. If rectifier 22 is of the vacuum type, the usual type of control electrode may be utilized. If rectifier 22 is however of the vapor type, the control electrode must be capable of removing the positive ionic charges present in the space between the anode and the control electrode at a rate greater than the rate of appearance of ions within such space. Such appearance of ions may be the result of collisions between electrons and vapor atoms or of wandering of ions from the space outside the control electrode through the openings thereof. In addition to the above mentioned removal of ionic charges, the control electrode should cause repulsion of the electrons produced at the cathode or in the space outside the control electrodes so as to prevent any further transport of charges to the anode.

To obtain such result without resorting to the energization of the control electrode at such high potential as to introduce disturbances in the operation of the rectifier the dimensions of the control electrode cannot be chosen arbitrarily but must be within predetermined limits. It has been found, for instance, that the desired result can be obtained by means of a control electrode having the openings thereof, which are available for the passage of the discharge, so dimensioned that the ion sheaths formed about the several portions of the control electrode structure entirely fill such openings when the control electrode is unenergized and is not traversed by the arc. In addition to the above mentioned overlapping of the ion sheaths, it is preferable to provide the openings in such numbers that their total area is approximately equal to forty percent of the area of the anode in contact with the discharge, to make the distance between the control electrode and the anode substantially equal to the mean free path of

the electrons, and to provide the area of the control electrodes in contact with the space contained between such electrode and the associated anode, plus the total area of the surfaces of such control electrode forming the openings thereof, equal to at least two and one-half times the total cross sectional area of such openings. It will be understood, however, that some control electrodes of dimensions other than the above are also suitable for obtaining the desired result.

The discharge occurring at such anode 21 is preferably also caused to come in contact with another electrode 25 connected with the anode through a resistor 27, the purpose of such electrode being to carry an uncontrolled current ionizing the discharge path of the anode and also to dissipate the surges appearing at the anode upon interruption of the flow of current therethrough by means of the control electrodes. The different phase portions of windings 15 and 16 are severally connected with further anodes 28 of rectifier 22 similar to anodes 21 and similarly provided with control electrodes 29 and with auxiliary electrodes 31 connected with the anodes through resistors 32.

Control electrodes 24 and 28 are connected through two groups of resistors 33 and 34 and two further groups of resistors 36 and 37 with the negative terminal of a source of direct current such as a battery 38. The two terminals of battery 38 are connected with a voltage divider 39 having an intermediate tap connected with cathode 23, thereby causing the potentials of the terminals of battery 38 to be in definite relation with the potential of cathode 23. The positive terminal of battery 38 is connected through contacts 41 of a relay 42 with the brushes 43 and 44 of two distributors 45 and 47. Brush 43 is driven at a speed in fixed relation with the voltage cycle of line 6 by suitable means such as a synchronous motor 48 having an armature winding connected with line 6 and a field structure 51 provided with a plurality of circumferentially spaced windings. Brush 44 is likewise driven by a synchronous motor 52 having an armature winding 53 energized from line 6 and a field 54 similar to field 51.

The windings of fields 51 and 54 are preferably energized from battery 38, the distribution of current through the several portions of each winding being regulated by means of a regulator 56. Such regulator comprises a torque producing element 57 energized in a manner depending upon the method of regulation desired. In the present embodiment element 57 is connected across line 7, 8 through a rheostat 58 to thereby become responsive to the magnitude of the voltage of line 7, 8. Element 57 may also be further energized in function of the magnitude of the current in conductor 8 by connection thereof with a shunt 59 and an adjusting rheostat 61. The torque of element 57 is opposed to the torque of suitable restraining means such as a spring 60 to cause the regulator to take different positions in dependence upon the values of the voltage of line 7, 8 and of the current in conductor 8.

The regulator is provided with one or more movable contact sectors such as 62 and 63 rocking in operative contact with one or more resistors such as 64 and 66. In the present embodiment, sectors 62 and 63 are severally connected with the terminals of battery 38 while resistors 64 and 66 are connected with the terminals, not connected with the battery, of fields 51 and 54 respectively. Due to this arrangement,

fields 51 and 54 are similarly energized when regulator 56 is in the position shown and, upon movement of the regulator, the energization of fields 51 and 54 is so modified as to cause field 51 to lag and field 54 to lead with respect to the rotating magnetic fields which are produced in windings 49 and 53 as a result of the energization thereof from line 6. Relay 42 is energized from a current transformer 68 inserted in the connection between line 6 and winding 9 and operates upon occurrence of excessive flow of current through current transformer 68 to open contacts 41 and to connect the positive terminal of battery 38 with cathode 23 through a second pair of contacts 69.

In operation, assuming line 6 to be energized, winding 9 receives current therefrom and induces identical six-phase voltages in windings 12 and 13 and in windings 14 and 16. In the absence of control electrodes in rectifier 22, windings 12 and 13 would carry current, at a comparatively high lagging power factor, to be rectified through anodes 21 and delivered to line 7, 8. In a similar manner, windings 14 and 16 would carry current at also a comparatively high lagging power factor and to be rectified through anodes 23 operating in parallel with the corresponding anodes 21. The output voltages of windings 12 and 13 and windings 14 and 16 would then be identical and simultaneous flow of current therethrough would be obtained at every instant even in the absence of interphase transformer 19.

Such operation is variably modified by the action of control electrodes 24 and 29, which are generally maintained at a negative potential with respect to the potential of the cathode 23 by means of battery 38. Upon energization of line 6, motor armatures 49 and 53 are energized therefrom and motors 48 and 52 may be started by any well known means and brought to approximately synchronous speed. Energization of field 51 and 54 with direct current then causes such motor to operate in synchronism with the voltage cycle of line 6. It will be assumed that, when regulator 56 is in the position shown, motors 48 and 52 drive brushes 43 and 44 in a manner such that a positive electromotive force is impressed thereby on each control electrode at the instant at which the associated anode becomes positive with respect to the anode or anodes previously carrying the discharge, and is removed when the associated anode becomes negative with respect to the anode or anodes to which such discharge is to be transferred. The control electrodes are then without effect on the flow of current through rectifier 22 and do not cause any regulation of the output voltage thereof.

Flow of such current may therefore occur through rectifier 22 and causes line 7, 8 to become energized at the maximum voltage thereof and energize the windings of element 57 of the regulator 56. Element 57 then produces a torque overcoming the torque of spring 69, thereby causing sectors 62 and 63 to rock and change the points of contact thereof with resistors 64 and 66. The flow of current through fields 51 and 54 is thereby varied in such manner that field 51 lags and field 54 leads with respect to the rotating field of the associated armatures. The times of energization of control electrodes 24 are thereby retarded and the times of energization of control electrodes 29 are advanced. Control electrodes 24 therefore sequentially re-

lease and interrupt the flow of current through the several anodes 21 at times of the voltage cycle later than the times of initiation and termination of such flow of current in the absence of control electrodes, thereby causing the flow of current from windings 12 and 13 through anodes 21 to occur at a reduced effective voltage; the reduction of such voltage is affected to an extent depending upon the extent of the movement of regulator 56 and the extent of the resulting lag of brush 43. As is well known, the flow of current through windings 12 and 13 then occurs at a reduced lagging power factor commensurate with the extent of reduction of the voltage of line 7, 8. Interphase transformer 18 continues to operate in the normal manner thereof, only the voltages appearing across the terminals thereof are of larger magnitudes than the voltages present in the absence of regulation by means of control electrodes.

Control electrodes 29, on the other hand, sequentially release and interrupt the flow of current through the associated anodes 23 prior to the times of initiation and termination of the flow of current therethrough in the absence of control electrodes to supply current to line 7, 8 at the same effective rectified voltage as anodes 21. Windings 14 and 16 then carry current substantially equal in magnitude to the current in windings 12 and 13 and flowing at a reduced leading power factor substantially equal in magnitude to the lagging power factor of the current in windings 12 and 13. Interphase transformer 17 operates in the normal manner thereof similarly to interphase transformer 18. With proper selection of the transformation ratio of transformer 11, the current flowing through winding 9 and received by such winding from line 6 is equal to the sum of the currents flowing through all the secondary windings and is therefore substantially in phase coincidence with the voltage or, in other words, the current flow occurs at substantially unity power factor.

Windings 12 and 13 and windings 14 and 16 supply current to line 7, 8 at average voltages of equal magnitudes but differing at every instant as a result of the presence of different alternating components therein resulting from the action of the control electrodes. Such components appear across the terminals of interphase transformer 19, and flow of current occur simultaneously at every instant through all the secondary windings and is delivered to line 7, 8 at the average effective voltage of all the windings. Regulator 56 continues its movement until the voltage of line 7, 8 is reduced to an extent such that the torque of element 57 becomes equal to the torque of spring 69. Regulator 56 then stops and maintains the voltage of line 7, 8 at a value depending upon the adjustment of rheostats 58 and 61.

In the above explanation it was assumed that the secondary windings of transformer 11 had equal reactances so that equal flows of current would occur therethrough if the lag of control electrodes 24 was exactly equal to the lead of control electrodes 29. It may be found, however, that the effective output voltages of windings 12 and 13 and of windings 14 and 16 actually are not exactly equal. The equality of the voltages may be restored by making the lag of control electrodes 24 slightly different in magnitude from the lead of control electrodes 29, for instance by suitably modifying resistor 64 or resistor 66.

As a result of the above method of operation, control electrodes 24 and 29 with battery 33 and distributors 46 and 52 constitute means for controlling the flow of current through anodes 21 and 28, through which the control electrodes are operable to release and also to interrupt the flow of current. Transformer 11, which connects rectifier 22 with line 6 and with line 7, 8 has distinct duplicate windings 12, 13 and 14, 16 to which the groups of anodes 21 and 28 are connected. Distributors 46 and 52 sequentially impress recurring electromotive forces from battery 48 on the several control electrodes 24 and 29, such electromotive forces being operable to cause a regulated flow of current to occur through rectifier 22. Such flow of current is controlled by regulator 56, which operates automatically in response to an electrical condition of the system to maintain the voltage line 7, 8 at predetermined values. The flow of current through the system between line 6 and rectifier 22 occurs at substantially unity power factor, the flow of current through anodes 21 being retarded and the flow of current through anodes 25 28 being advanced. Such result is obtained by simultaneously advancing the impression of the electromotive forces on one group of control electrodes and retarding the impression of electromotive forces on the other group of control 30 electrodes. The flow of leading current in windings 14 and 16 and of lagging current in windings 12 and 13 are of substantially equal magnitudes and result in flow of substantially equal amounts of energy therethrough between the 35 two lines.

In the embodiment illustrated in Figure 2 it is assumed that windings 9, 12 and 13 are arranged on a first magnetic structure to constitute a first transformer 71 while windings 14 and 16 are arranged on a second magnetic structure with another primary winding 72 energized from line 6 to constitute a second transformer 73. In order to generalize the scope of the invention it is also assumed that, in the present embodiment, 45 windings 12 and 13 and windings 14 and 15 are of different voltages and have different current ratings. Anodes 21 and 28 may again be arranged in a single rectifier 22 or may be arranged in two separate rectifiers 74 and 77 having two 50 cathodes 76 and 78 connected with conductor 8. In this manner it is therefore possible to construct a unit system by means of two independent rectifying systems of different construction.

Control electrodes 24 and 29 may be energized in a manner similar to that illustrated in Figure 1 or in any other suitable manner. For instance, control electrodes 24 may be energized from the star connected secondary winding of a transformer 78 energized from line 6 and control 60 electrodes 29 may be energized in a similar manner from a second transformer 81. The neutral point of the secondary winding of transformer 78 is preferably maintained at a variable negative potential with respect to the potential of cathode 76 such as by means of a voltage divider connected between conductors 7 and 9 and comprising resistor 64 and adjusting rheostats 63 and 64. The negative electromotive force 65 impressed between conductor 8 and the neutral point of the secondary winding is then the voltage drop in the rheostats and in the resistor between such neutral point and conductor 8. The regulation of such electromotive force results from the action of regulator 56, in which sector 70 63 is operatively connected to short circuit a

variable amount of resistor 64. The flow of current may be maintained uniform in the voltage divider by means of a reactor 82. Transformer 81 is similarly associated with a voltage divider comprising rheostats 87 and 89, a reactor 86 and 5 the resistor 88 of a second regulator 91 arranged similarly to regulator 56 but with the restraining means of very reduced effect or even entirely omitted.

The torque element of regulator 91 may be 10 connected as element 57, but is more advantageously energized in response to electrical conditions of interphase transformer 19 such as the signs and magnitudes of the direct current voltage components which appear across the terminals of such interphase transformer. The connection between the regulator 91 and interphase transformer 19 may be variably effected through taps of the interphase transformer winding or of a voltage divider 90 and preferably comprises a reactor 92 for preventing the flow of alternating current through the coil of regulator 91.

The operation of anodes 21 is controlled in the same manner in the present embodiment and in 25 the embodiment illustrated in Figure 1. In the present embodiment both the positive and negative electromotive forces impressed on control electrodes 24 result from the combination of the voltages of transformer 79 and of the associated 30 voltage divider. The output voltage of rectifier 74 is therefore maintained at values depending on the adjustment of regulator 56, and the flow of current between line 6 and winding 9 occurs at a lagging power factor having a magnitude 35 depending upon the degree of regulation produced by regulator 56.

Control electrodes 29 are not controlled directly in dependence upon the voltage of line 7, 8 but are controlled in a manner such as to cause the 40 average output voltage of rectifier 77 to be equal to the average output voltage of rectifier 74. If such average voltages are not equal, the difference therebetween appears across the terminals of interphase transformer 19 and causes a flow 45 of current through the coil of regulator 91. Regulator 91 then operates to vary the negative direct current voltage current component impressed on control electrodes 29 to thereby adjust the times of energization of control electrodes 29 50 55 at positive and at negative potentials with respect to the potential of cathode 78. Such action continues until the output voltages of rectifiers 74 and 77 are equal and a direct current voltage component is no longer present in interphase 60 transformer 19, regulator 91 then remaining in the position reached thereby. Regulator 91 is so connected that the regulating action thereof causes an advance in the times of energization of control electrodes 29 to thereby cause rectifiers 77 to receive current at a leading power factor from line 6. It will be understood that operation of regulator 91 to regulate the flow of current through rectifier 77 will also cause the magnitude of the current through rectifier 65 74 to change, and regulator 56 must then operate further to compensate for the action of regulator 91.

In the present embodiment also the total current drawn from line 6 may therefore be maintained substantially in phase with the voltage. If the phase voltages of windings 12 and 13 and windings 14 and 16 are equal, the lead given to control electrodes 24 will be substantially equal to the lag given to control electrodes 29 to obtain 70 75

equal output voltages for rectifiers 74 and 77. If the phase voltages of windings 14 and 16, for instance, are greater than the phase voltages of windings 12 and 13, the lead of control electrodes 29 will have to be increased as compared to the lag of control electrodes 24 to reestablish the equality of the output voltages. The result of such control will then be that all windings will again carry currents of equal magnitudes, but the leading power factor of the current in transformer 73 will be smaller than the lagging power factor of the current in transformer 71 and the total current drawn from line 6 will be leading. A flow of lagging total current would be obtained by adjusting windings 12 and 13 to deliver phase voltages greater than the phase voltages of windings 14 and 16.

If the two transformers are of different current carrying capacities it is preferable to adjust the winding portions of interphase transformer 19 with numbers of turns in inverse ratio to the amounts of current to be carried thereby. The connection of interphase transformer 19 with regulator 91 should then be so adjusted that the winding of regulator 91 receives no current when the flows of current through the two portions of the interphase transformer are in the desired proportion. Regulator 91 then will control the energization of control electrodes 29 to cause rectifiers 74 and 77 to deliver average voltages of substantially equal magnitudes while maintaining the output currents thereof in the desired proportion, whereby current operation of interphase transformer 19 is again obtained. Windings 12 and 13 and windings 14 and 16 then carry currents of different magnitudes at relative values of power factor depending upon the relative values of the phase voltages of such windings. By varying the adjustment of the magnitudes of phase voltages and the adjustment of interphase transformer 19, windings 9 and 72 may be made to receive from line 6 currents of magnitudes and power factors in any desired relation, and therefore the total flow of current between line 6 and rectifiers 74 and 77 may be adjusted to occur at any desired leading or lagging power factor.

In the present embodiment therefore windings 12, 13 and 14, 16 are of different voltages, but although such windings are shown as forming parts of separate transformers they could equally as well be arranged in a single transformer structure. Similarly rectifiers 74 and 77 could be replaced by a single rectifier such as rectifier 22. Regulators 56 and 91 cooperate to perform the functions performed by regulator 56 alone in the embodiment illustrated in Figure 1. Such regulators permit obtaining flow of electrical energy at different leading and lagging power factors in the windings of the transformers, thereby causing the flow of current at any desired power factor between line 6 and rectifiers 74 and 77. Such lagging and leading currents always flow at substantially the same effective or average terminal voltage. Although regulators 56 and 91 act cooperatively, they operate independently for severally adjusting the impression of electromotive forces on the one and on the other group of control electrodes.

Although but two embodiments of the present invention have been illustrated and described, it will be apparent to those skilled in the art that various changes and modifications may be made therein without departing from the spirit of the

invention or from the scope of the appended claims.

It is claimed and desired to secure by Letters Patent:

1. In a system for controlling the flow of electric current, an electric current circuit, a second electric current circuit, electron discharge means having a plurality of anodes and a cathode, means for connecting said discharge means with each of said circuits, a plurality of control electrodes severally operable to release and to interrupt the flow of current through said anodes, a source of electromotive force connected with said cathode, means for continually impressing electromotive forces from said source on said control electrodes, and means controlling the last said means and operable to simultaneously advance the impression of said electromotive forces on some of said control electrodes and retard the impression of said electromotive forces on others of said control electrodes. 5 10 15

2. In a system for controlling the flow of electric current, an alternating current circuit, an electron discharge device connected with said circuit and having a plurality of anodes and a cathode, a direct current circuit connected with said circuit and with said discharge device, a plurality of control electrodes severally operable to release and to interrupt the flow of current through said anodes, a source of electromotive force connected with said cathode, means for continually impressing electromotive forces from said source on said control electrodes, and means controlling the last said means and operable to simultaneously advance the impression of said 25 30 35 electromotive forces on some of said control electrodes and retard the impression of said electromotive forces on others of said control electrodes.

3. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to release and to interrupt the flow of current through 45 50 55 said groups of anodes, a source of electromotive force connected with said cathode, means for continually impressing electromotive forces from said source sequentially on the several control electrodes of each group to cause a regulated flow of current to be established through said discharge device, and means controlling the last said means and operable to simultaneously advance the moments of impression of said electromotive forces on the control electrodes of one group and 60 65 retard the moments of impression of said electromotive forces on the control electrodes of the other group.

4. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups, and severally operable to release and to interrupt the flow of current through said groups of anodes, a source of elec- 70 75

tromotive force connected with said cathode, means for continually impressing electromotive forces from said source sequentially on the several control electrodes of each group of such sign and magnitude and during such recurring moments as to cause flow of leading current in one of said distinct windings and of lagging current in another of said distinct windings.

5. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes in two groups severally operable to release and to interrupt the flow of current through said 10 groups of anodes, a source of electromotive force connected with said cathode, means for continually impressing electromotive forces from said source sequentially on the several control electrodes of each group of such sign and magnitude as to cause each control electrode to control the establishment of said arcs by way of the associated anode and to effect the interruption thereof at such moments as to cause flow of current at substantially unity power factor between said alternating current circuit and said 15 transformer.

6. In a system for controlling the flow of electric current, an alternating current circuit, a transformer connected with said circuit and having a plurality of windings, an electron discharge device having two groups of anodes connected with duplicate windings of said transformer and having a cathode, a direct current circuit connected with said transformer and with 20 said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said 25 duplicate windings and of lagging current of equal magnitude in the other of said duplicate windings.

7. In a system for controlling the flow of electric current, an alternating current circuit, a transformer connected with said circuit and having a plurality of windings of different voltages, an electron discharge device having two groups of anodes connected with windings of different voltages of said transformer and having a cathode, a direct current circuit connected with said transformer and with said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of electrical energy at leading and lagging power factors respectively of different values through said windings of different voltages.

8. In a system for controlling the flow of electric current, an alternating current circuit, a

transformer connected with said circuit and having a plurality of windings of different voltages, an electron discharge device having two groups of anodes connected with windings of different voltages of said transformer and having a cathode, a direct current circuit connected with said transformer and with said discharge device, control electrodes in two groups and severally operable to release and to interrupt the flow of current through said groups of 10 anodes, a source of electromotive force connected with said cathode, means for continually impressing electromotive forces from said source sequentially on the several control electrodes of each group of such sign and magnitude and during such moments as to cause flow of leading current in one of said windings of different voltages and lagging current at the same effective voltage in the other of said windings of different voltages.

9. In a system for controlling the flow of electric current, an alternating current circuit, an electron discharge device connected with said circuit and having a plurality of anodes and a cathode, a direct current circuit connected with said circuit and with said discharge device, a plurality of control electrodes severally operable to release and to interrupt the flow of current through said anodes, a source of electromotive force connected with said cathode, means for continually impressing electromotive forces from said source on said control electrodes of such sign and magnitude as to cause each control electrode to control the establishment of said arcs by way of the associated anode and to effect the interruption thereof at such moments as to cause flow of current at any desired power factor between said alternating current circuit and said discharge device.

10. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said distinct windings and lagging current in the other of said distinct windings, and means controlling the last said means and operable to simultaneously advance the impression of said electromotive forces on the control electrodes of one group and retard the impression of said electromotive forces on the control electrodes of the other group.

11. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to

release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said distinct windings and lagging current in the other of said distinct windings, and means controlling the last said means and operable coextensively to simultaneously advance the impression of said electromotive forces on the control electrodes of one group and retard the impression of said electromotive forces on the control electrodes of the other group.

tinually impressing electromotive forces from said source sequentially on the several control electrodes of each group of such sign and magnitude and during such moments as to cause flow of leading current in one of said distinct windings and lagging current in another of said distinct windings, and an interphase transformer connecting said transformer with said direct current line.

12. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said distinct windings and lagging current in another of said distinct windings, and independent means for severally adjusting the impression of said electromotive forces simultaneously on the one and on the other groups of said control electrodes.

13. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said distinct windings and lagging current in another of said distinct windings, and independent means for severally adjusting the impression of said electromotive forces simultaneously on the one and on the other groups of said control electrodes.

40 13. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said distinct windings and of lagging current in another of said distinct windings, and means for causing flow of current simultaneously through the one and the another of said windings at every instant.

14. In a system for controlling the flow of electric current, an alternating current circuit, 65 a transformer connected with said circuit and having a plurality of windings, an electron discharge device having two groups of anodes connected with distinct windings of said transformer and having a cathode, a direct current circuit 70 connected with said transformer and with said discharge device, control electrodes arranged in two groups and severally operable to release and to interrupt the flow of current through said groups of anodes, a source of electromotive force 75 connected with said cathode, means for con-

15. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said distinct windings and lagging current in another of said distinct windings, and means responsive to an electrical condition of said system controlling the last said means and operable to simultaneously advance the impression of said electromotive forces on the control electrodes of one group and retard the impression of said electromotive forces on the control electrodes of the other group.

16. In a system for controlling the flow of electric current, an alternating current circuit, a transformer connected with said circuit and having a plurality of windings, an electron discharge device having two groups of anodes connected with distinct windings of said transformer and having a cathode, a direct current circuit connected with said transformer and with said discharge device, control electrodes arranged in two groups and severally operable to release and to interrupt the flow of current through said groups of anodes, a source of electromotive force connected with said cathode, means for continually impressing electromotive forces from said source sequentially on the several control electrodes of each group of such sign and magnitude and during such moments as to cause flow of leading current in one of said distinct windings and lagging current in another of said distinct windings, and automatic means controlling the last said means and operable to simultaneously advance the impression of said electromotive forces on the control electrodes of one group and retard the impression of said electromotive forces on the control electrodes of the other group.

17. In a system for controlling the flow of electric current, an alternating current circuit, an electron discharge device connected with said circuit and having a plurality of anodes and a cathode, a direct current circuit connected with said circuit and with said discharge device, a plurality of control electrodes severally operable to release and to interrupt the flow of current through said anodes, a source of electromotive force connected with said cathode, means for continually impressing electromotive forces from said source on each said control electrode to cause the release of said flow of current by way 70 75

of the associated anode and to effect the interruption thereof, and regulating means cooperating with the last said means to vary the moments of said impression of said electromotive forces to cause flow of current at substantially unity power factor between said alternating current circuit and said discharge device.

18. In a system for controlling the flow of electric current, an alternating current circuit, 10 a transformer connected with said circuit and having a plurality of secondary windings, an interphase transformer joining the secondary windings of said transformer, said interphase transformer having a plurality of portions with 15 unequal numbers of turns, an electron discharge device with separate groups of anodes connected with the secondary windings of said transformer and a cathode, a direct current circuit connected with said interphase transformer and with the cathode, control electrodes severally associated 20 with the anodes, means for energizing said control electrodes, and means controlling the last said means and operable to simultaneously advance the flow of current through one group 25 of the anodes and retard the flow of current through the other group of the anodes to obtain unity power factor between said alternating current line and said device.

19. The combination with an alternating current supply circuit, a load circuit, and means 30 interconnecting said circuits comprising an electron discharge device having a cathode and a plurality of anodes divided into groups and constituting spaced electrodes for the flow of current between said circuits by way of arcs when 35 established between said anodes and cathode, of means comprising control electrodes severally associated with said anodes and so dimensioned and disposed relative to the associated anodes 40 as to be operable to control the establishment of said arcs and to effect the interruptions thereof, means comprising sources of current having connections with said cathode and continually impressing electromotive forces sequentially on the 45 several control electrodes associated with the said anodes of each group thereof of such signs and magnitudes as to cause each control electrode to control the establishment of said arcs by way of the associated anode and to effect the 50 interruption thereof at such moments as to thereby cause the said flow of current from said supply circuit at any desired power factor.

20. The combination with an electric current supply circuit, a load circuit, one of said circuits 55 being an alternating current circuit, and means interconnecting said circuits comprising an electron discharge device having a cathode and a plurality of anodes divided into groups and constituting spaced electrodes for the flow of current 60 between said circuits by way of arcs when established between said anodes and cathode, of means comprising control electrodes severally associated with said anodes and so dimensioned and disposed relative to the associated anodes 65 as to be operable to control the moments of establishment of said arcs and the moments of interruption thereof, means comprising a source of current having connection with said cathode and continually impressing electromotive forces 70 sequentially on the control electrodes associated with the said anodes of each group thereof of such signs and magnitudes and during such moments as to control the moments of establishment of said arcs and the moments of inter-

ruption thereof, and means operable to simultaneously advance the moments of impression of said electromotive forces on the control electrodes associated with the anodes of one of said groups thereof and retard the moments of impression of said electromotive forces on the control electrodes associated with the anodes of another of said groups thereof, whereby leading current is caused to flow through the anodes of the said one group thereof and lagging current 10 through the anodes of the said another group thereof.

21. The combination with an alternating current supply circuit, a load circuit, and means interconnecting said circuits comprising an electron discharge device having a cathode and a plurality of anodes divided into groups and constituting spaced electrodes for the flow of current between said circuits by way of arcs when established between said anodes and cathode, 20 of means comprising control electrodes severally associated with said anodes and so dimensioned and disposed relative to the associated anodes as to be operable to control the moments of establishment of said arcs and the moments of interruption thereof, means comprising a source of current having connection with said cathode and continually impressing electromotive forces sequentially on the control electrodes associated with the anodes of each group thereof of such 30 sign and magnitude and during such moments relative to the voltage frequency of the said supply circuit as to control the moments of establishment of said arcs and the moments of interruption thereof, means operable to simultaneously advance the moments of impression of said electromotive forces on the control electrodes associated with the anodes of one of said groups thereof and retard the moments of impression of said electromotive forces on the control electrodes associated with the anodes of another group thereof, and means operable responsive to and in dependence on the flow of energy in one of said circuits for controlling the 35 operation of the fourth said means, whereby 40 current at any desired power factor is caused to flow from one to another of said circuits.

22. The combination with an alternating current supply circuit, a load circuit, and electron discharge means interconnecting said circuits comprising a cathode and a plurality of anodes constituting spaced electrodes for the flow of current by way of arcs when established therebetween, of means comprising control electrodes severally associated with said anodes and so dimensioned and disposed relative thereto as to be operable to control the establishment of said arcs and to effect the interruption thereof, means comprising a source of current having connection with said cathode and continually 60 impressing electromotive forces sequentially on said control electrodes of such signs and magnitude as to cause each control electrode to control the establishment of said arcs by way of the associated anode and to effect the interruption thereof, and means operable responsive to and in dependence on changes in an operating condition of said system and cooperating with the fourth said means to vary the moments of the impressions of said electromotive forces on 65 said control electrodes, to thereby cause said flow of current to occur at a predetermined 70 power factor.
